ELECTRICAL TRANSFORMER

Roger B. Kerr, Marblehead, Mass., assignor to General Electric Company, a corporation of New York

Application December 22, 1955, Serial No. 39,428

Term of patent 14 years

(Cl. D26—15)

Fig. 1

Fig. 2

Fig. 3

Figure 1 is a perspective view showing the front and one end of an electrical transformer embodying my new design,

Figure 2 is a side elevation taken from the back of the transformer shown in Figure 1, and

Figure 3 is an end elevation taken from the right of the same.

I claim:

The ornamental design for an electrical transformer, as shown.
